UNITED STATES PATENT OFFICE.

HERMOND L. MCCORMACK, OF MENARD, ILLINOIS, ASSIGNOR OF ONE-HALF
TO WILLIAM A. STORM, OF NEOGA, ILLINOIS.

JEWELER'S BRAZING-LAMP.

SPECIFICATION forming part of Letters Patent No. 656,654, dated August 28, 1900.

Application filed October 5, 1899. Serial No. 732,666. (No model.)

To all whom it may concern:

Be it known that I, HERMOND L. MCCORMACK, a citizen of the United States, residing at Menard, in the county of Randolph and State of Illinois, have invented a new and useful Improvement in Jewelers' Brazing-Lamps, of which the following is a specification.

This invention is an improved construction 10 of brazing-lamp particularly adapted for jewelers' use, the object being to provide an exceedingly cheap, simple, and efficient device by means of which a jet-flame of intense heat can be secured; and with these objects 15 in view the invention consists in the peculiar construction of the various parts and in their novel combination and arrangement, all of which will be fully described hereinafter and pointed out in the claims.

20 In the drawings forming part of this specification, Figure 1 is a side elevation of a lamp constructed in accordance with my invention. Fig. 2 is a vertical sectional view. Fig. 3 is a detail of the jet-nozzles, and Fig. 25 4 shows a slight modification.

In carrying out my invention I employ a suitable tank A, having an inlet-opening A' at the top, which is normally closed by means of a stopper or plug which may act as a safety-30 valve. The tank A is preferably constructed in spherical form and is provided with an exterior circumferential rib or flange adapted to rest upon a suitable support B. The tank or receptacle A is intended to receive alcohol, and the pipe C is located within the said tank or receptacle, the upper end thereof extending nearly to the top of the same, while the lower end is projected out of the said tank in a horizontal direction at the bottom 35 40 of the said tank, the outer end of said pipe being provided with a jet-nozzle C', said jet-nozzle being removable, so that different sizes or styles of jets can be employed, according to the character of the flame desired. The support B is substantially semicircular and has its ends bent down at right angles thereto to form legs B², and its central portion is secured to a rod or bar B³, which also forms a leg as well as a handle by which it may be 45 50 carried. The upper end of the rod is prefer-

ably provided with an opening, by means of which it may be suspended from the wall. Secured to said legs, near the bottom, is a suitable base-plate B'. A spirit-lamp of any desired construction is adapted to rest upon the base-plate B', with its burner directly in line with the end of the pipe and its jet-nozzle. In operation the spirit-lamp is lighted, thereby vaporizing the alcohol within the tank, which vapor passes through the pipe C out 60 through the jet-nozzle and commingles with the flame from the spirit-lamp, thereby producing a vapor jet-flame equal in intensity, if not greater, than the heat of a blowpipe-flame. By means of this construction it will 65 be seen that I provide a brazing-lamp consisting of very few parts and by means of which a fine jet-flame can be obtained.

In Fig. 4 I have shown a slight modification in which the tank and spirit-lamp are supported upon the tripod by means of chains E, and the spirit-lamp is preferably constructed with two burners, one adapted to rest directly beneath the jet-nozzle and the other some distance in advance, so that the vapor-jet will 70 75 commingle with the flame in advance of the nozzle.

Having thus fully described my invention, what I claim as new, and desire to secure by Letters Patent of the United States, is— 80

1. In a brazing-lamp, the combination, with a stand provided with three legs, the upper ends of two of which are provided with a substantially-semicircular support, and the other leg secured to the intermediate portion of said support and extended above the same, of a receptacle upon the support the bottom of which is provided with an outlet, and means for supporting a lamp below the receptacle in position to cause its flame to impinge upon 85 90 said outlet, substantially as described.

2. In a brazing-lamp, the combination with a rear rod, the upper end of which is provided with an opening, of a support secured thereto, said support being semicircular and having its ends bent at an angle to form legs, and means for supporting a receptacle and a lamp thereon. 95

3. In a brazing-lamp, the combination, with a rear rod, the upper end of which is pro- 100

vided with an opening, of a support secured to the intermediate portion of the rod, said support being semicircular and having its ends bent at an angle to form legs, a base-
5 plate secured to said legs and to the rear rod near the lower ends thereof, a receptacle upon the support provided with a bead and a nozzle, and a lamp under the nozzle, substantially as described.

HERMOND L. McCORMACK.
